TENT STRUCTURE

John W. Dixon, Waco, Tex.

Application April 25, 1936, Serial No. 76,334

2 Claims. (Cl. 135—4)

This invention relates to tents and it has particular reference to the structure of the supports and fabric covering for tents, especially those employed for funerals and the like, and the method of erecting the same.

One of the principal objects of the invention is to provide in a tent, a main supporting structure comprised principally of two major elements, each supporting a side of the cover or tent and consisting of a leg and a rafter hinged to the top of the leg. The invention affords specifically such an element as set forth but capable of collapsibility whereby it may be confined in a space sufficiently small as to enable it to be carried as part of the burial equipment in a hearse or like vehicle.

Another object of the invention is to provide a foldable tent leg, a support and anchor, in addition to a connecting means to join two of the legs to define a securing means for the apex or ridge-rail, depending upon the style of tent desired.

The present invention is an improvement upon the structure described in Letters Patent #1,969,260 issued jointly to the applicant and Paul A. Filer, Aug. 7, 1934.

Another object of the invention is to provide certain improvements in a tent covering, the latter having provisions in the nature of straps, snaps and webbing co-operating with the elements of the supporting structure in such manner as to reduce to a minimum the amount of time and effort ordinarily required to erect a tent of conventional construction.

Still another object of the invention is to provide an improved method of erecting a tent or temporary shelter, the steps comprising, first, in securing to the cover elements of the supporting structure, then in progressively raising to upright position the supporting elements of the cover and finally in securing the elements against relative displacement.

With the foregoing objects as paramount, the invention has particular reference to its salient features of construction and arrangement of parts and to the method set forth which will become manifest as the description proceeds, taken in connection with the accompanying drawings, wherein, Figure 1 is a perspective view of a tent, with portions broken away to show the invention.

Figure 2 is a view of the invention per se in elevation, broken to show extension.

Figure 3 is a detail view of the connecting member for the tent legs, partly broken away.

Figure 4 is a detail view of the hinge.

Figure 5 shows a tent leg constructed according to the invention in folded position, and

Figure 6 is a detail perspective view of a leg rest or foot with anchor.

Figure 7 is a fragmentary view of a tent constructed according to the present invention with portions of the cover broken away to reveal parts of the supporting structure.

Figure 8 is a fragmentary view of the corner of the tent showing the elements by which the cover is secured to the supporting structure and by which the structure is guyed to the ground.

Figure 9 is a transverse section through one of the tent posts on lines 9—9 on Figure 7.

Figure 10 is a fragmentary view of the means by which the side walls of the tent are suspended from the cover, and

Figure 11 is a fragmentary view of the apex of the top of the tent showing the means for connecting thereto the roof supporting structure.

Continuing with a more detailed description of the drawings, reference is primarily made to Figure 1 in which 1 designates the corner supports for the cover or canopy 2. As many of these posts as required may be used to construct tents of different styles and for different uses. Each post has a pin 3 in its upper end which is received by a ring or loop terminus 3a of the reinforcing member 4 of the canopy which member I prefer to be of a webbing or other material having proper strength and which will have the same degree of expansion and contraction as the canvas cover during atmospheric variations.

To allow for ready movement for perpendicular aligning of the legs 1, and to provide an anchor therefor, members 5 such as shown in detail in Figure 6 are employed. These members or feet are comprised of substantially square metal plates whose corners are turned upward to prevent them from interfering with sliding movement over the ground. A collar 6 is affixed centrally to the plate to receive the leg 1 and an aperture is provided in the plate to receive an anchor stake 7.

Guy ropes 8 are operably connected to the pins 3 of the legs 1 as by loop or terminus 3a for convenience, and to stakes 9 driven in the earth. The reinforcing members 4 extend to the apex or ridge-rail of the structure, as well as about its edges, thus defining a supporting or reinforcing structure for the cover.

One of the objects of this particular type of construction, as set forth in the above identified patent, is to eliminate the necessity for a center pole. This pole or other conventional support

ing means for the tent is of great annoyance when a tent is used for cemeteries as a shelter for funerals. It has been found that more extensive use of the tent may be had with greater convenience in handling by providing for foldability of elements of the supporting structure with complementary parts cooperating to insure proper rigidity in use and compactness when folded.

Accordingly the invention comprising the legs 10, the lower ends resting in members 5 and having their upper ends angularly cut as at *a*, to correspond with the similarly shaped end of the section *b* of the rafter 11. Connecting rafter section *b* and leg 10 is a hinge of peculiar design, shown particularly in Figure 2. The strap 12 of the hinge is bolted to the leg 10 and the companion part of the hinge is secured to the rafter section *b*. This part of the hinge is comprised of plates 13, affixed on either side of the section *b*, each provided with a flange *c*. Apertures in these flanges register with the loop of hinge plate 12 to receive a pintle 14. Thus the hinge reinforces, by virtue of the overreaching flanges *c*, the hinged elements. In a similar manner, the section *b* of the rib 11 is secured to an extension section *d*. The ends are contiguous at right angles with respect to their longitudinal axis and the hinge plate 15 is affixed to the section *d*, while the plates 16 are bolted on either side of section *b*. The flanges *e* of the plates 16 are apertured to receive a pintle 17.

Section *d* is shaped into a cylindrical pin 18 to be received in the tubular arm 19 of the A-shaped connecting member 19. This pin may be reinforced by means of a metal ferrule or similar device 18a. This member is comprised in the present case, of a length or tubular material, flattened intermediate its ends and bent 40 in U-shape at *f*, (Fig. 3). Extending upward from this bend is a pin 20, which protrudes through a suitably reinforced opening in the cover 2 of the tent, which opening preferably provides termini for members 4. A bar 21 reinforces the member 19 and the arrangement assembled affords a rigid support for the sides and roof of the tent. A shoulder portion 20a holds the tent cover away from the rafter preventing friction and wear between these elements which 45 greatly prolongs the life of the tent cover. Other reinforcing means includes the chain 22 which extends from one section *b* to the other (Fig. 1) and when the assemblies are in folded position the chain may be conveniently wound about the elements in the manner shown in Figure 5.

In Figures 7 to 11 inclusive is shown the manner and method of securing the top and sides of the tent to the supporting structure just described. In this connection, reference is primarily made to Figure 7 in which is shown the cover or canopy 2 having webbing or reinforcing member same as 4 but here indicated as 23 about the edges or eaves of the tent ordinarily overlapped by skirt parting or border 24. A cord 25 extends along the webbing 23 and is attached thereto at intervals and serves the dual purpose of affording added reinforcement to the tent cover and providing a supporting means for the walls 26 of the tent which are suspended by means of hooks 27, connected to the said walls 26 and overreaching the cord 25.

In Figure 8 is shown a preferred form of the tent, the top or cover 2 having a reinforced aperture 28, to receive each of the pins 3 carried by the posts 10. A ring 29, suspended by means of

a strap from the reinforcement of the aperture 28 serves as a means of securement for each of the several guy ropes 8, (which latter may directly connect with aperture 28 if preferred), while the snap 30 engages the ring 31, (Figures 5 2 and 5) secured to each of the tent legs 10, thus to hold the cover in fixed relation to the supporting structure. Corner posts 1 may also be provided with rings 31 for receiving snaps 30.

The walls 26 of the tent are provided with 10 straps 32 (Figures 7 and 9). One wall is wrapped partially around a leg 1 of the tent and a contiguous wall embraces both the leg 1 and the portion of the adjacent wall surrounding the leg. Straps 32 are snapped into position to hold the 15 edges of the wall sections in this relative position after being first passed through suitable apertures in the first wall section.

The members 19 preferably are first connected to the cover or canopy 2 in order to properly erect the tent. The means for thus securing the members is comprised of straps 33, secured in the apex 20 of the canopy 2 and their ends are passed between the bifurcations of the U-shaped upper end *f* of the member 19. By thus securing the canopy 25 2, the tent may be erected on a windy day without a great amount of trouble.

It is apparent from the foregoing that a tent that may be folded into a compact bundle is provided of a length no greater than the length 30 of the legs 1 of the tent.

Such compactness enables one to place the tent in a container capable of being carried in a hearse or like vehicle.

One of the novel characteristics of this tent structure is that one man is enabled to erect a tent of considerable proportions, even in rough weather, in a very short time, which he may proceed to do in the following manner. Stakes for the guy ropes are driven with proper relation to the site on which the tent is to be erected. A corner of the tent is so positioned as to receive the contact of any breeze prevailing at the time it is unrolled and the proper lengths of corresponding guy ropes are secured to the corner stakes, the spike extension 3 of a corner post is passed through the reinforced rings of the canopy 2 and snap member 30 may be engaged with ring member 31 on the post where the latter are employed. The next and succeeding corners of the tent are in like manner secured to the stakes, and the shoe or plate placed under the first corner post which latter then is moved into upright position followed by the other corner posts. The guy ropes are adjusted as required to effect the proper tension on the eaves of the tent, the apex of which will then be swinging downwardly, whereupon the operator brings the A-shaped member 19 into position and passes its pin 20 through ring member 3a and passes strap 33 through opening in the A-shaped member which is then buckled. Sections 18 of folding supporting ribs 11 having been inserted in the ends of the A-shaped member and chain 22 joined so as to effect a proper relation of the folding ribs 65 and relieve them of undue spreading strain under the working load. The operator then passes pin 3 of one of the legs through aperture 28 of ring 3a of the eave of the tent and secures snap 30 in ring 31 of the section 10 of the leg which latter is presently to be brought into upright position. The guy ropes at these points may be secured to the tent and the stakes at any convenient time, but are brought under proper tension upon erection to the vertical of members 10. 70 75

The complementary upright section 10 of the folding rafter structure is next similarly brought into operative position and is followed in like manner by other of the folding rafter members.

5 Thus the erection of the tent is readily and safely accomplished by one man. Dismantling of the tent may readily be effected by a reversal of the foregoing procedure.

Manifestly, the construction shown is capable 10 of considerable modification and such modification as is considered within the scope and meaning of the appended claims is also considered within the spirit and intent of the invention.

What is claimed is:

15 1. In a tent supporting structure, a pair of legs each having a rafter joined end to end therewith at an angle thereto, each rafter in sections and having their upper ends free, the upper end of each leg and the contiguous end of a respective

rafter being bevelled and hinged together, the said sections of each rafter being also hinged together whereby they are foldably related and foldable with respect to said leg, means receivable by the free ends of said rafters to provide a peak support for said tent.

2. In a tent supporting structure, a pair of legs each having a rafter joined end to end therewith at an angle thereto, each rafter in sections and having their upper ends free, the upper end of each leg and the contiguous end of a respective rafter being bevelled and hinged together, the said sections of each rafter being also hinged together whereby they are foldably related and foldable with respect to said leg, means receivable by the free ends of said rafters to provide a peak support for said tent and guy lines supporting the said legs.

JOHN W. DIXON.
